[57] **CLAIM**

The ornamental design for a golf ball collector, as shown and described.

DESCRIPTION

FIG. 1 is a front perspective view of a golf ball collector, showing my design;

FIG. 2 is a right side elevation view thereof;

FIG. 3 is a rear elevation view thereof;

FIG. 4 is a top plan view thereof;

FIG. 5 is a front elevation view thereof; and,

FIG. 6 is a bottom plan view thereof.

The broken line showing of golf balls is for illustrative purposes only and forms no part of the claimed design.
